UNITED STATES PATENT OFFICE.

HUGH F. McDERMOTT, OF JERSEY CITY, NEW JERSEY.

SEAL FOR ENVELOPES.

SPECIFICATION forming part of Letters Patent No. 406,056, dated July 2, 1889.

Application filed November 28, 1888. Serial No. 292,052. (No model.)

To all whom it may concern:

Be it known that I, HUGH F. McDERMOTT, a citizen of the United States, residing at Jersey City, in the county of Hudson and State of New Jersey, have invented new and useful Improvements in Seals for Envelopes, of which the following is a specification.

The invention relates to improvements in seals for envelopes; and it consists in a certain novel construction and combination of devices, fully described hereinafter in connection with the accompanying drawings, and specifically pointed out in the appended claim.

15 In the drawings, Figure 1 is a view of the improved seal applied in the operative position to an envelope. Fig. 2 is a vertical central sectional view of the same. Fig. 3 is a detail perspective view of the seal with the parts detached. Fig. 4 is a similar view of the inner disk, showing the points in the position which they assume when the disks are connected. Fig. 5 is a view of the blank of the inner disk.

25 Referring by letter to the drawings, A designates the inner disk, which is adapted to be arranged within the envelope *a*, and it is provided at its periphery with the outstanding points or fingers *B B*, (preferably integral with the disk and struck from the same sheet of metal,) which are pressed through the rear side *a'* of the envelope and the flap *a''*, which folds thereon. It is obvious that as

30 the ends of the points or fingers are sharpened or pointed they may be readily forced through the material composing the envelope.

The outer disk *C* is slightly convexed outwardly, and is provided at its periphery with the inturned ears *D D*, provided with transverse slots or perforations *E E*. This outer disk is placed over the inner disk, the points or fingers of the latter are introduced into the slots or perforations *E E*, and the two disks are pressed together. This pressure causes the extremities of the points or fingers to bear on the outer disk and bend inward. After the disks are thus connected or engaged together they cannot be separated, except by forcing them apart by a suitable

tool, and thereby straightening the points or fingers. This cannot be accomplished without tearing or defacing the envelope to which the seal is applied, thereby indicating to the proper parties that the envelope has been tampered with.

55 It is obvious that the seal will operate as described if the outer plate is flat; but I prefer to convex it outwardly, as described, as the rounded shape facilitates the inward bending of the points or fingers, and also provides space between the disk and the envelope for the accommodation of the said points after they are bent.

Two points or fingers and a corresponding number of perforated ears are sufficient for 65 the operation of the seal; but I do not limit myself to any particular number. I may employ two or more.

To further facilitate the inward bending of the extremities of the points or fingers, they 70 are inclined slightly in the direction of the periphery of the disk, thereby causing them to slide more freely on the outer disk when the latter is engaged therewith. Fig. 5 illustrates the blank of the inner disk with the 75 points or fingers formed integral therewith, and it will be seen that the said points are not formed in continuation of the radii of the disk, but are inclined thereto, whereby, when they are bent outward perpendicular to the 80 plane of the disk, they are inclined slightly in the direction of the periphery or at a tangent to the periphery.

The improved seal, as will be seen, is very simple in construction, consisting merely of 85 two disks provided, respectively, with perforated ears and points to engage the ears, the said disks being struck from sheet metal by a single operation.

The seal is applied by arranging the inner 90 disk within the envelope, pushing the points through the rear side of the latter and the flap, placing the perforated ears over the outer ends of the points, and pressing the outer disk toward the inner disk until the former 95 bears against the envelope.

Having thus described the invention, I claim—

The herein-described seal formed of two disks A and C, the first mentioned being provided with projecting spurs tangentially inclined and at an angle to the face of the disk 5 and the last mentioned being provided with inwardly-bent slotted ears and adapted to receive the spurs, as specified.

In testimony that I claim the foregoing as my own I have hereto affixed my signature in presence of two witnesses.

HUGH F. McDERMOTT.
